UNITED STATES PATENT OFFICE.

WILLIAM J. LINDSAY, OF PHILADELPHIA, PENNSYLVANIA, ASSIGNOR TO CAMDEN IRON WORKS, OF CAMDEN, NEW JERSEY, A CORPORATION OF NEW JERSEY.

GAS-PRODUCER.

1,160,516.

Specification of Letters Patent. Patented Nov. 16, 1915.

Application filed November 12, 1913. Serial No. 800,585.

To all whom it may concern:

Be it known that I, WILLIAM J. LINDSAY, a subject of the King of Great Britain and Ireland and the Isle of Man, residing in 5 Philadelphia, county of Philadelphia, State of Pennsylvania, have invented certain Improvements in Gas-Producers, of which the following is a specification.

My invention relates to certain improvements in gas producers of the type in which the body of the producer rotates and the stirring or slicer bars are suspended from a fixed frame and extend into the body portion.

15 One object of my invention is to provide means for rotating the stirring or slicer bars to agitate the material while it is being carried by the rotating casing.

A further object of the invention is to 20 provide means by which the stirring or slicer bars are held in the position to which they are adjusted.

In the accompanying drawings the figure 25 is a vertical sectional view of a gas producer illustrating my invention.

Referring to the drawings, 1 is a base on which the gas producer is mounted.

2 is a rotating body portion of the producer.

30 3 is an air pipe extending into the cone 4. The producer is sealed in the ordinary manner, as shown.

5 is a worm wheel on the body portion and meshing with this wheel is a worm 6 on 35 a driving shaft 7 by which the body portion of the producer is rotated. Other driving mechanism may be used without departing from the essential feature of the invention.

The body portion, in the present instances, 40 rests upon a series of flanged wheels 8, mounted in bearings, as shown in Fig. 1.

9, 9 are beams located at each side of the producer and supported on these beams, independently of the producer, is a beam 10 45 which carries the stirring bars 11.

12 is the top section of the producer and this section is stepped; the portion 13 being less in height than the portion 14. In the portion 14 is a fuel opening and gas outlet. 50 The joint between the rotating body 2 and the top section 12 is sealed, in the present instance by a water seal 15.

The above construction is fully set forth and described in the patent granted to

Claude M. Garland, No. 1,079,234, dated 55 November 18, 1913.

In the present instance, there are two slicer bars arranged at one side of the transverse central line of the producer. The bars are arranged at different distances from the center so that each of the bars, as the body portion rotates, will cut its own path in the coking coal. Each slicer bar has a curved lower section 16 and one of the bars has a greater curve than the other, consequently, it has a more extended sweep. Each slicer bar is rotated as the body portion rotates, therefore, the entire mass of the fuel bed is agitated and kept in motion as the body portion rotates. Each bar passes through an opening 17 in the beam 10 and has a worm wheel 18 splined thereto so that the bar must turn with the worm wheel.

19 is a driven shaft having worms 20 which mesh with the worm wheels 18, so that, as 75 the shaft 19 rotates, a rotary motion will be imparted to each of the slicer bars. In some instances a stationary bar may be mounted in the bearings 28 in the beam 10, and one of the other bars may be stationary and only 80 one rotate, without departing from the spirit of the invention.

The shape of the lower end of the stirring bar may be varied according to circumstances. In the present instance, each stirring bar has a longitudinal spline 21 adapted to receive a key secured to the worm wheel, so that the stirring bar can be vertically adjusted to any point desired, but will always turn with the worm wheel. In 90 order to hold the stirring bar in the position to which it is adjusted, transverse grooves 22 are made in the stirring bar at a given distance apart and a two-part collar 23 having a rib on its inner surface is clamped 95 to the stirring bar, the rib entering any one of the grooves 22. This collar is held between the upper end of the worm wheel 18 and a bearing 24 supported by standards 25 on the beam 10. The weight of the stirring bar is taken by the bearing 26 on which rests the extended hub of the worm wheel 18. The stirring bar passes through a suitably packed stuffing box 27 in the top section of the producer, as clearly shown 100 in Fig. 1. The stirring bar is water cooled

105 in the ordinary manner common to this type of apparatus.

It will be seen by the above construction that, as the body of the producer rotates, one or more of the stirring bars also rotates around its own axis and cuts a path in the fuel bed. The paths may be arranged close together or far apart, according to the speed of rotation of the stirring bar and where two bars are arranged to rotate, as in the drawing, then one bar will cut through the 10 path of the other bar, completely stirring the fuel bed.

As stated above, one or all of the bars may be adjusted vertically so as to bring them in line, as shown in the drawing, or 15 out of line, as desired.

I claim:—

1. The combination in a gas producer, of a rotating body portion; a fixed top section having two openings therein spaced different 20 distances from the center of rotation of the body portion; a fixed beam extending directly above the top section and independently supported; two stirring bars carried solely by the beam and extending through 25 the openings in the top section, said stirring bars being bent out of line; means for rotating each bar, said bars being vertically adjustable; and means for retaining the bars in the adjusted position.
2. The combination in a gas producer, 30 of a rotating body portion; a fixed top section; a fixed beam extending over the top section; a stirring bar mounted on the fixed beam and extending through the top sec-

tion and into the body portion, the lower 35 portion of the stirring bar projecting at one side of its center line; a gear wheel through which the stirring bar extends; said stirring bar being splined; a key on the gear wheel entering the spline so that the stirring bar 40 must turn with the gear wheel; means for retaining the stirring bar in the position to which it is adjusted; and means for rotating the body portion of the gas producer.

3. The combination in a gas producer, 45 of a rotating body portion; a fixed top section; a fixed beam extending over the top section; a bearing on the beam; a stirring bar extending through the beam and through the said bearing and having a lon- 50 gitudinal spline; a driving wheel mounted on the beam and having a key engaging the spline so that the stirring bar will turn with the wheel, the bar having a series of 55 annular grooves; and a two-part collar having a rib arranged to enter one of the grooves, said collar being located between the gear and the bearing so as to retain the stirring bar in the position to which it is adjusted.

In testimony whereof, I have signed my name to this specification, in the presence of two subscribing witnesses.

WILLIAM J. LINDSAY.
